UNITED STATES PATENT OFFICE.

BARTON PICKERING JENKS, OF CONCORD, NEW HAMPSHIRE, ASSIGNOR TO WM. B. DURGIN CO., OF CONCORD, NEW HAMPSHIRE, A CORPORATION OF NEW HAMPSHIRE.

DESIGN FOR A HANDLE FOR SPOONS, FORKS, OR SIMILAR ARTICLES.

40,971.

Specification for Design.

Patented Nov. 8, 1910.

Application filed July 20, 1910. Serial No. 572,946. Term of patent 14 years.

To all whom it may concern:

Be it known that I, BARTON PICKERING JENKS, citizen of the United States, residing at Concord, in the county of Merrimack and State of New Hampshire, have invented a new, original, and ornamental Design for Handles for Spoons, Forks, or Similar Articles, reference being had to the accompanying drawings.

The figure is a view in perspective of the handle showing my design.

I claim—

The ornamental design for a handle for spoons, forks or similar articles, as shown and described.

BARTON PICKERING JENKS.
